Primary Examiner — Sheryl Lane*Assistant Examiner* — Ieisha Price(74) *Attorney, Agent, or Firm* — Sheridan Ross P.C.(57) **CLAIM**

The ornamental design for a vehicle rack bracket, as shown and described.

DESCRIPTION

FIG. 1 is a top perspective view of a vehicle rack bracket; FIG. 2 is a bottom perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof;

FIG. 8 is a bottom plan view thereof; and,

FIG. 9 is an environmental perspective view of the vehicle rack bracket.

The broken lines in the drawings illustrate portions of the vehicle rack bracket or a rack that the vehicle rack bracket is interconnected to and form no part of the claimed design.
